US00D877804S

(12) **United States Design Patent** (10) **Patent No.:** **US D877,804 S**
(45) **Date of Patent:** **** Mar. 10, 2020**

(54) **ELECTRONIC EYEGLASSES**

(71) Applicant: **Mitsui Chemicals, Inc.**, Tokyo (JP)

(72) Inventors: **Hortense Desodt**, San Francisco, CA (US); **Thomas Overthun**, San Francisco, CA (US)

(73) Assignee: **Mitsui Chemicals, Inc.**, Tokyo (JP)

(**) Term: **15 Years**

(21) Appl. No.: **29/619,643**

(22) Filed: **Sep. 29, 2017**

(51) LOC (12) Cl. **16-06**

(52) U.S. Cl.

USPC **D16/335**

(58) **Field of Classification Search**

Mitsui Chemicals Gets Ready to Bring Electronic Eyewear to market, announced Oct. 5, 2017, [online], [site visited Jul. 7, 2018]. Available from Internet, <URL: <https://www.japanchemicaldaily.com/2017/10/05/mitsui-chemicals-gets-ready-to-bring-electronic-eyewear-to-market/>> (Year: 2017)*

Primary Examiner — Michelle E. Wilson

Assistant Examiner — Sanjeev Paul

(74) *Attorney, Agent, or Firm* — Sterne, Kessler, Goldstein & Fox P.L.L.C.

CLAIM

The ornamental design for electronic eyeglasses, as shown and described.

DESCRIPTION

FIG. 1 is a top front perspective view of electronic eyeglasses showing the claimed design;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof;

FIG. 8 is an enlarged view of a left-side portion thereof;

FIG. 9 is a top front perspective view of electronic eyeglasses showing the claimed design;

FIG. 10 is a front view thereof;

FIG. 11 is a rear view thereof;

FIG. 12 is a top view thereof;

FIG. 13 is a bottom view thereof;

FIG. 14 is a right side view thereof;

FIG. 15 is a left side view thereof; and,

FIG. 16 is an enlarged view of a left-side portion thereof. The dashed broken lines in the figures show portions of the electronic eyeglasses that form no part of the claimed design.

The dot-dash broken lines in the figures show boundaries that form no part of the claimed design.

1 Claim, 16 Drawing Sheets
